WAYNE K. HAWK, OF PHILADELPHIA, PENNSYLVANIA.

MECHANISM FOR MAKING PILE FABRICS.

Application filed March 30, 1926. Serial No. 98,448.

Pile carpet usually consists of linen warps, filler warps, a pile warp and linen wefts. The pile warp is looped over wires and a weft thread binds the pile warp between each pair of wires. This produces a carpet with a soft upper face and a hard under face whereas it is highly desirable that the under face be soft. Such carpet may be produced by introducing an under weft of soft thread alternating with one or more of the hard linen wefts, but this requires the use of two shuttle boxes at each side of the machine. Owing to the necessarily fixed position of the wire slide upon looms of the Brussels-Wilton type, the use of two shuttle boxes on the side of the loom which carries the wire slide has been considered impractical.

The primary object of my invention is to provide mechanism which will adapt looms of the Brussels-Wilton type to making pile carpets with soft backs. Another object is to adapt such looms to making pile carpets in which one shoot of soft weft is alternated with two shoots of linen or other hard weft. These objects, and other advantageous ends which will be described hereinafter, I attain in the following manner, reference being had to the accompanying drawings in which—

30 Figure 1 is a fragmentary end view of a loom of the Brussels-Wilton type embodying my invention,

Figure 2 a section on line 2—2 of Figure 1,

35 Figure 3 a fragmentary end view similar to that of Figure 1 but showing my invention in a modified form,

Figure 4 a section on line 4—4 of Figure 3 with certain parts broken away,

40 Figure 5 a detail of part of the mechanism shown in Figures 3 and 4,

Figure 6 a detail of the mechanism shown in Figure 5 but viewed at right angles to Figure 5,

45 Figure 7 a fragmentary section through the fabric showing the arrangement of the threads and the looping of the pile threads over the wires,

Figure 8 an exaggerated plan view of the fabric shown in Figure 7, and

50 Figure 9 a plan view of the picker stop.

Referring to Figures 1 and 2 of the drawings, the numeral 1 indicates the frame of the loom, 2 the driving shaft of the loom, 3 a grooved cam fixed to the shaft, 4 a rod, 55 slidable in a bearing 5, carrying at one end

a roller 6 taking into the groove of cam 3, and carrying at the other end a cam track 7, 8 a rock shaft on which swords 9 are fixed, there being a sword at each end of 60 the loom, 10 the shuttle race carried by the swords, 11 the reed, also carried by the swords, 12 the wire slide, 13 a lever fulcrumed upon the sword at 14, and carrying at its upper end a support 15 for shuttle boxes 16 and 17 disposed side by side and below the wire slide. The lower end of the shuttle lever has a lateral extension 18 provided with a slot 19 enclosing rock shaft 8 and carrying at its free end a roller 20 taking into cam track 7. Driving shaft 2 carries a large gear 21 meshing with a small gear 22 on a shaft 23. Cranks 24 on shaft 23 are connected by a link 25 with swords 9. The ratio between gears 21 and 22 is 3 70 to 1, consequently one revolution of drive shaft 2 will cause swords 9 to rock forwardly and rearwardly three times. Cam 3, through its associated parts rocks shuttle box lever 13 intermittently relatively to 80 swords 9, and its cam track is so formed that shuttle box 16 which carries the linen thread will be held in alignment with the shuttle race 10 during two reciprocations of the swords, the shuttle box lever then rocked to 85 shuttle box 17, which carries the soft thread, into alignment with the shuttle race, where it will be held during one reciprocation of the swords, and the shuttle lever rocked in reverse direction to again bring 90 shuttle box 16 into alignment with the shuttle race, thus completing a cycle.

A picker stick 26 is pivotally mounted on a collar 27 fixed to rock shaft 8 and a picker stop 28 is fixed to the rock shaft. 95

Inasmuch as the shuttle boxes move laterally to bring one or the other into alignment with the shuttle race and the picker stick must act alternately upon different shuttle boxes, the slot in which the picker 100 slides is made with an open end as shown at 29 in Figure 9, the picker stop is provided with a corresponding slot 30 into which the picker may slide, and the picker stick is connected with the shank of the picker stop by 105 a coiled spring 31 which acts to carry the picker stick beyond the shuttle box support and into slot 30.

The modification shown in Figures 3 and 4 produces the same result. The swords 110 are rocked in the same manner as in Figures 1 and 2 and by like mechanism but the

shuttle boxes are disposed one above the other and are operated by different mechanism. A sleeve 32 is loosely mounted on rock shaft 8 and held against longitudinal movement thereon by collars 33. A sleeve 34, having a longitudinal slot 35, extends upwardly from sleeve 32. The shuttle boxes are carried by a rod 36 slidable in sleeve 34 and carrying at its lower end a roller 37 which takes into a cam track in a cam 38 rotatably mounted on rock shaft 8. A sprocket 39 fixed to cam 38 is connected by a sprocket chain 40 with a sprocket 41 fixed to driving shaft 2. An arm 42 extends from sleeve 34 and carries a roller 43 which takes into a cam track in a cam 44 fixed to the drive shaft. The picker stick 26^a is pivotally mounted on sleeve 32. Cam 38 will be rotated, through sprocket chain 40, at the same speed as the driving shaft but its track is so formed that shuttle box 17^a, carrying the linen thread, will be held in alignment with the shuttle race during two reciprocations of the swords, then raised to bring shuttle box 16^a into alignment with the shuttle race, the shuttle box held in alignment during one reciprocation of the swords, and then lowered to bring shuttle box 17^a into alignment with the shuttle race. The reciprocatory movement of the shuttle support and shuttle boxes, due to cam 44 is such that the shuttle boxes will advance with the swords and at the same speed during a limited part of the throw of the swords and then move at a slower speed so that the maximum movement of the shuttle boxes is less than that of the swords. The shuttle box support being distinct from the shuttle race, the race will complete its movement leaving a gap between it and the shuttle box support. Upon the return movement the shuttle box support moves at slower speed than the shuttle race until the gap is closed, the picking action being effected while the gap is closed. The maximum outward movement of the shuttle box support is so limited that the shuttle boxes do not engage the wire slide.

In Figures 7 and 8, 45 indicates the wires, *a* the filler warp, *b* the binder warps, *c* the pile thread, *d* the binder wefts and *e* the soft weft.

While I have described and shown the shuttle box support as carrying two shuttle boxes, it is obvious that the number of shuttle boxes may be increased if found desirable.

It will be understood that, on the other side of the loom, the usual arrangement of vertically movable shuttle boxes may be used.

Having thus described my invention, what I claim as new and desire to secure by Letters Patent is:—

65 1. In a loom having a wire guide and a

sword at either end; a support, adapted to carry a plurality of shuttle boxes in such a manner as to clear the wire guide, mounted upon one of the swords, and means to oscillate the shuttle box support independently from the sword. 76

2. In a loom having a wire guide and a sword at either end; a support, adapted to carry a plurality of shuttle boxes in such a manner as to clear the wire guide, mounted upon one of the swords; and means to rock the shuttle box support so as to bring a shuttle box into alignment with the shuttle race and to hold same in such alignment during one or more reciprocations of the sword, then rock the shuttle box support to bring another shuttle box into alignment with the shuttle race and to hold same in such alignment during one or more reciprocations of the swords. 75 80 85

3. In a loom, a drive shaft; a rock shaft; swords fixed to the rock shaft; connections between the drive shaft and the swords whereby the swords will be reciprocated; a shuttle race carried by the swords; a lever fulcrumed upon a sword; a shuttle box support carried by the lever; a plurality of shuttle boxes, disposed side by side, carried by the lever, the lever being so positioned that the shuttle boxes do not interfere with the wire guide on the loom, and connections between the drive shaft and the lever whereby the lever will be rocked to move a shuttle box into alignment with the shuttle race, then held to retain the shuttle box in such alignment during one or more reciprocations of the swords, then rocked to move the other shuttle box into alignment with the shuttle race, then held to retain the shuttle box in such alignment during one or more reciprocations of the swords, then rocked to move another shuttle box into alignment with the shuttle race. 90 95 100 105

4. In a loom, a drive shaft; a rock shaft; swords fixed to the rock shaft; connections between the drive shaft and the swords whereby the swords will be reciprocated; a shuttle race carried by the swords; a lever fulcrumed upon a sword; a shuttle box support carried by the lever; a plurality of shuttle boxes, disposed side by side, carried by the lever, the lever being so positioned that the shuttle boxes do not interfere with the wire guide on the loom, and connections between the drive shaft and the lever whereby the lever will be rocked to move a shuttle box into alignment with the shuttle race, then held to retain the shuttle box in such alignment during two reciprocations of the swords, then rocked to move the other shuttle box into alignment with the shuttle race, then held to retain the shuttle box in such alignment during a reciprocation of the swords, then rocked to move another shuttle box into alignment with the shuttle race. 110 115 120 125 130

5. In a loom, a drive shaft; a rock shaft; swords fixed to the rock shaft; connections between the drive shaft and the swords whereby the swords will be reciprocated; a shuttle race carried by the swords; a lever fulcrumed upon a sword; a shuttle box support carried by the lever; a plurality of shuttle boxes, disposed side by side, carried by the lever, the lever being so positioned that the shuttle boxes do not interfere with the wire guide on the loom; a cam fixed to the drive shaft; connections between the cam and the shuttle box lever whereby the lever will be rocked to move a shuttle box into alignment with the shuttle race, then held to retain the shuttle box in such alignment during one or more reciprocations of the swords, then rocked to move the other shuttle box into alignment with the shuttle race, then held to retain the shuttle box in such alignment during one or more reciprocations of the swords, then rocked to move another shuttle box into alignment with the shuttle race.
25. 6. In a loom, a drive shaft; a rock shaft; swords fixed to the rock shaft; connections between the drive shaft and the swords whereby the swords will be reciprocated; a shuttle race carried by the swords; a lever fulcrumed upon a sword; a shuttle box support carried by the lever; a plurality of shuttle boxes, disposed side by side, carried by the lever, the lever being so positioned that the shuttle boxes do not interfere with the wire guide on the loom; a cam fixed to the drive shaft; connections between the cam and the shuttle box lever whereby the lever will be rocked to move a shuttle box into alignment with the shuttle race, then held to retain the shuttle box in such alignment during two reciprocations of the swords, then rocked to move the other shuttle box into alignment with the shuttle race, then held to maintain it in such alignment during a reciprocation of the swords.
40. 7. In a loom, a drive shaft; a rock shaft; swords fixed to the rock shaft; connections between the drive shaft and the swords whereby the swords will be reciprocated; a shuttle race carried by the swords; a lever fulcrumed upon a sword; a shuttle box support carried by the lever; a plurality of shuttle boxes, disposed side by side, carried by the lever, the lever being so positioned that the shuttle boxes do not interfere with the wire guide on the loom; an arm projecting laterally from the lower end of the lever; a roller carried thereby; a grooved cam fixed to the drive shaft; a rod slidably mounted in the frame carrying at one end a roller taking into the cam track and, at the other end, a cam track engaging the roller on the shuttle lever, the first mentioned cam track being so formed that, through its connections with the shuttle lever, the lever will be rocked to move one shuttle box into alignment with the shuttle race, then held to maintain such alignment during one or more reciprocations of the swords, then rocked to move another shuttle box into alignment with the shuttle race, then held to maintain such alignment during one or more reciprocations of the swords.
45. 8. In a loom, a drive shaft; a rock shaft; swords fixed to the rock shaft; connections between the drive shaft and the swords whereby the swords will be reciprocated; a shuttle race carried by the swords; a lever fulcrumed upon a sword; a shuttle box support carried by the lever; a plurality of shuttle boxes, disposed side by side, carried by the lever, the lever being so positioned that the shuttle boxes do not interfere with the wire guide on the loom; an arm projecting laterally from the lower end of the lever; a roller carried thereby; a grooved cam fixed to the drive shaft; a rod slidably mounted in the frame carrying at one end a roller taking into the cam track and, at the other end, a cam track engaging the roller on the shuttle lever, the first mentioned cam track being so formed that, through its connections with the shuttle lever, the lever will be rocked to move one shuttle box into alignment with the shuttle race, then held to maintain such alignment during one or more reciprocations of the swords, then rocked to move another shuttle box into alignment with the shuttle race, then held to maintain such alignment during one or more reciprocations of the swords.
50. 9. In a loom having a wire guide, a drive shaft; a rock shaft, swords fixed to the rock shaft; connections between the drive shaft and the swords whereby the swords will be reciprocated; a shuttle race carried by the swords; a lever fulcrumed upon a sword; a plurality of shuttle boxes carried by the lever and disposed side by side; connections between the drive shaft and the lever whereby the lever will be rocked to successively move the shuttle boxes into alignment with the shuttle race without interference from the wire guide, the shuttle boxes having an open ended slot adapted to receive a picker stick; a picker stop having an open ended slot adapted to receive a picker stick and a picker stick mounted to swing with the shuttle box support and to take into the slots.
60. 10. In a loom having a wire guide, a drive shaft; a rock shaft, swords fixed to the rock shaft; connections between the drive shaft and the swords whereby the swords will be reciprocated; a shuttle race carried by the swords; a lever fulcrumed upon a sword; a plurality of shuttle boxes carried by the lever and disposed side by side; connections between the drive shaft and the lever whereby the lever will be rocked to successively move the shuttle boxes into alignment with the shuttle race without interference from the wire guide, the shuttle boxes having an open ended slot adapted to receive a picker stick; a picker stop having an open ended slot adapted to receive a picker stick and a picker stick mounted to swing with the shuttle box support and to take into the slots.

between the drive shaft and the lever whereby the lever will be rocked to successively move the shuttle boxes into alignment with the shuttle race without interference from the wire guide, the shuttle boxes having an open ended slot adapted to receive a picker stick; a picker stop having an open ended

slot adapted to receive a picker stick and a picker stick pivotally mounted upon the rock shaft and adapted to take into the slots.

In testimony whereof I have signed my name to this specification.

WAYNE K. HAWK.
